UNITED STATES PATENT OFFICE.

JAMES H. THAYER, OF CHICAGO, ILLINOIS.

AUTOMATIC TIGHTENER FOR BED-SPRINGS.

No. 823,824.

Specification of Letters Patent.

Patented June 19, 1906.

Application filed January 22, 1906. Serial No. 297,183.

To all whom it may concern:

Be it known that I, JAMES H. THAYER, a citizen of the United States, residing at Chicago, in the county of Cook and State of Illinois, have invented certain new and useful Improvements in Automatic Tighteners for Bed-Springs, of which the following is a specification.

This invention relates to improvements in an apparatus or attachment to be used on bedsteads for automatically stretching or tightening the web or wire fabric which sustains the mattress and the bedclothes and which web or fabric may be of woven wire or other suitable material and of the ordinary or any preferred construction; and it consists in certain peculiarities of the construction, novel arrangement, and operation of the various parts thereof, as will be hereinafter more fully set forth and specifically claimed.

The principal object of the invention is to provide an apparatus of the above-named character which shall be simple and inexpensive in construction, strong, durable, and effective in operation, and which shall be so made that it may be readily placed in position on the bed-frame or removed therefrom and when in use its parts will be hidden from view.

Other objects and advantages of the invention will be disclosed in the subjoined description and explanation.

In order to enable others skilled in the art to which my invention pertains to make and use the same, I will now proceed to describe it, referring to the accompanying drawings, in which—

Figure 1 is a view in side elevation of a bed, showing an automatic tightener for the web, fabric, or woven-wire mattress embodying my invention mounted thereon with the parts thereof in their normal positions. Fig. 2 is a view, partly in elevation and partly in section, taken on line 2-2 of Fig. 4 looking in the direction of the arrows, of a portion of the web or mattress-supporting fabric and parts of the tightener. Fig. 3 is a rear end elevation of the parts shown in Fig. 2. Fig. 4 is a cross-sectional view taken on line 4-4 of Fig. 5 looking in the direction indicated by the arrows. Fig. 5 is a similar view taken on line 5-5 of Fig. 1 looking in the direction indicated by the arrows. Fig. 6 is an outer face view of one of the pairs of gears and ratchet-wheels used on the winding-shaft of the tightener.

Fig. 7 is a horizontal sectional view thereof. Fig. 8 is an enlarged view in elevation of a portion of one of the supporting brackets for the winding-shaft and operating-shaft and a part of the frame of the tightener, 60 showing gears and ratchets mounted on said bracket and a portion of one of the operating-levers for the last-named shaft. Fig. 9 is a detached perspective view of one of the brackets of the tightener-frame which are located at the head of the bed, and Fig. 10 is a similar view of one of the brackets of said frame located at the foot of the bed-frame.

Like numerals of reference refer to corresponding parts throughout the different views of the drawings.

The reference-numerals 15 and 16 designate the upright portions of the head and foot, respectively, of the bed, which portions are united by the longitudinal and parallel 75 side rails 17 in the ordinary or any well-known manner, which rails are preferably made of angle-iron, as is clearly shown in Figs. 4 and 5 of the drawings, but may be of other shape, if desired. Mounted on the side rails 17 of 80 the bed-frame and between the same is the tightener-frame, which consists of two longitudinal and parallel side rails 18, which in the present instance I have shown as being tubular or circular in cross-section, but which 85 may be of other form, and means transversely uniting the members 18 at or near their ends and to hold them at a sufficient distance apart to permit the tightener-frame to be inserted between the side rails 17 of the 90 bed-frame.

Mounted on the front end of each of the rails 18 is a bracket 19, each of which has on its outer surface a horizontal extension 20 to rest on the upper surface of the side rail 17 of 95 the bed and each of which has on its inner surface an extension 21, provided with an opening 22 to receive the front end of the rail 18, as will be clearly understood by reference to Figs. 5 and 9 of the drawings.

The upper inner portion of each of the brackets 19 is provided with a vertical rib 23, terminating at its lower end with a lateral and horizontal offset 24 on each side thereof. The rib 23 is provided with openings 25 to 100 receive bolts used for securing the clamping-bars 26 and 27 at their ends to said ribs. These clamping-bars extend transversely of the rails 18, as shown in Fig. 5, and constitute a part of the tightener-frame, but are 110

employed for the further purpose of securing and sustaining the front end of the web, fabric, or woven-wire mattress 28, which is interposed at its front end between said bars, 5 as is clearly shown in Fig. 1 of the drawings.

Mounted on the rear or foot end of each of the side rails 18 of the tightener-frame is a bracket 29, each of which has on its inner surface an inward extension 30, provided with 10 an opening 31 to receive the rear ends of the rails 18, as will be clearly understood by reference to Figs. 1, 4, and 10 of the drawings.

Each of the brackets 29 has on its outer surface a horizontal and outward extension 15 32 to rest on the rails 17 of the bed-frame.

Each of the brackets 29 is provided with openings or bearings 33 and 34 for the stub-shafts 35 of the ratchets and gears mounted on the ends of the winding-shaft and operating-shaft, the former of which is preferably made of two pieces 36, semicircular in cross-section, as shown in Fig. 2 of the drawings. The members 36 of the winding-shaft 37 are 20 preferably enlarged from their ends to their middle portions, as shown in Fig. 4, and have 25 interposed between their flat surfaces the foot or rear end of the fabric 28 and are secured together by means of screw-bolts 38, so as to clamp the fabric therebetween, as 30 will be readily understood by reference to Fig. 2 of the drawings.

Secured on each end of the winding-shaft 37 is a combined ratchet-wheel 39 and gear 40, which are preferably formed integral, as 35 shown in Figs. 6 and 7, but may be made separately, yet each rigidly mounted on said shaft. When formed integrally, each of the gears 40 is provided with a socketed hub 41 to receive the ends of the members 36 of the 40 winding-shaft 37.

Each of the ratchet-wheels 39 is provided on its outer surface with a stub-shaft 35 to fit in the openings 33 of the brackets 29, so as to rotatably support the shaft 37 therebetween. Mounted on each end of the operating-shaft 42 is a ratchet 39 and 40, which 45 may be of the same construction as those used on the winding-shaft and above described.

Each of the ratchet-wheels 39 on the operating-shaft has on its outer surface a stub-shaft 35 to fit in the bearings 34 of the brackets 29, so as to rotatably support the shaft 42 between said brackets and in such a manner 55 that the gears 40 on the operating-shaft will mesh with the gears 40 on the winding-shaft.

Pivoted secured to each of the brackets 29 rearwardly from the ratchet-wheels 40 on the winding-shaft is a pawl 43, which are 60 held in loose engagement with the ratchets 39 on said shaft by means of springs 44, secured on said brackets. Loosely mounted at one of their ends on the operating-shaft 42 near each of its ends and between the rails 18 65 of the tightener-frame are levers 45, which

extend forwardly to about the middle of the bed-frame and have their front or free ends upturned, as is shown in Figs. 1 and 2 of the drawings.

Pivoted secured to the upturned ends of 70 the levers 45 is a transverse bar 46, which lies horizontally under the fabric 28 and may be attached thereto by means of staples or rivets 47 or otherwise.

Each of the levers 45 has pivoted thereon 75 near its secured end a pawl 48, which are held in loose engagement with the ratchet-wheels 39 on the shaft 42 by means of springs 49, which are secured on said levers.

While I have shown the winding-shaft 37 80 as being constructed of two semicircular members 36 and have illustrated the fabric 28 as being clamped between said members, yet I do not desire to be limited to such a construction of the shaft or the manner of securing the fabric thereto, as it is evident that the shaft may be made cylindrical and of one piece only and the fabric fastened thereto in any desired manner.

From the foregoing and by reference to the 85 drawings it will be seen and clearly understood that when the parts of the tightener are assembled, as above set forth, the tightener-frame carrying the winding-shaft and operating-shaft which serve to connect the rear ends of the side rails 18 and form a part 90 of said frame may be placed between the side rails 17 of the bed-frame, so that the extensions 20 and 32 of the brackets 19 and 29, respectively, will rest on the upper surface of 95 the rails of the bed-frame, and as the fabric 28 is secured at its front end between the transverse bars 26 and 27 and at its rear end to the winding-shaft 37 said fabric will be supported at a slight distance above the bed-frame, as is clearly shown in Fig. 1 of the 100 drawings.

When the parts are thus arranged, it is apparent that the levers 45, which support the transverse bar 46, will lie in a horizontal position until a sufficient 105 amount of weight—for instance, the body of a person—is placed on the fabric 28 to depress them, when, by reason of the pawls 48, which they carry, engaging the ratchet-wheels 39 on the operating-shaft, said shaft will be partially rotated, thus through the instrumentality of the gears 40 on the operating-shaft and the gears 40 on the winding-shaft, which mesh with one another, will cause the last-named shaft to be partially rotated, thus 110 taking up any undue slackness in the web or fabric 28 and holding the same taut, for it is apparent that the pawls 43, which engage the ratchets on the winding-shaft, will prevent the reverse movement thereof.

By tapering the winding-shaft 37 from its middle to its ends it is evident that the tension or strain on the middle portion of the fabric will thereby be increased so as to prevent the same sagging longitudinally at 115 120 125 130

its middle or forming into trough shape, as frequently occurs on account of the person using the bed sleeping in the middle thereof.

As the levers 45 are loosely mounted on the shaft 42, it is obvious that they will to a certain extent act independently of one another. For instance, when the weight of the body of the person is located on one edge of the bed one of said levers will be depressed, which movement will cause the operating-shaft and winding-shaft to be partially rotated. While I have shown the tightener provided with two levers and gears and ratchet-wheels at each of the ends of the shafts and prefer to so construct the apparatus, yet in some instances I may omit one of said levers and one of the said gears and ratchet-wheels.

Having thus fully described my invention, what I claim as new, and desire to secure by Letters Patent, is—

1. In a bed-spring tightener, the combination with the tightener-frame, of a winding-shaft transversely journaled thereon at one of its ends, a pinion on one end of said shaft, a web or fabric secured at one of its ends to one end of the frame and at its other end to the shaft, a pinion journaled on the frame and meshing with the pinion on the winding-shaft, a ratchet-wheel journaled to move in unison with the last-named pinion, a lever fulcrumed at one of its ends and having its other end adapted to engage the fabric, and a pawl on said lever to engage the ratchet-wheel, substantially as described.

2. In a bed-spring tightener, the combination with the tightener-frame, of a winding-shaft and an operating-shaft transversely journaled thereon in parallelism, intermeshing gears and ratchet-wheels on one of the ends of said shafts, a web or fabric secured at one of its ends to one end of said frame and at its other end to the winding-shaft, a lever mounted at one of its ends on the operating-shaft and in engagement at its other end with the web or fabric, and a pawl on the lever to engage the ratchet-wheel on the operating-shaft, substantially as described.

3. In a bed-spring tightener, the combination with the tightener-frame, of a winding-shaft and operating-shaft transversely journaled thereon in parallelism, intermeshing gears and ratchet-wheels on one of the ends of said shafts, a spring-pressed pawl to engage the ratchet-wheel on the winding-shaft, a web or fabric secured at one of its ends to one end of said frame and at its other end to the winding-shaft, a lever mounted at one of its ends on the operating-shaft and in engage-

ment at its other end with the web or fabric, 60 and a pawl on the lever to engage the ratchet-wheel on the operating-shaft, substantially as described.

4. In a bed-spring tightener, the combination with the tightener-frame, of a winding-shaft and operating-shaft transversely journaled thereon in parallelism, intermeshing gears and ratchet-wheels on both of the ends of said shafts, a web or fabric secured at one of its ends to one end of said frame and at 70 its other end to the winding-shaft, spring-pressed pawls to engage the ratchets on the winding-shaft, a lever mounted at one of its ends on the operating-shaft near each of its ends, a bar transversely uniting the other 75 ends of the levers and adapted to engage the fabric, and spring-pressed pawls on the lever to engage the ratchet-wheels on the operating-shaft, substantially as described.

5. In a bed-spring tightener, the combination with the tightener-frame, of a winding-shaft tapered from its middle toward each of its ends and an operating-shaft journaled transversely on said frame near one of its ends, intermeshing gears and ratchet-wheels 85 on both of the ends of said shafts, a web or fabric secured at one of its ends to one end of said frame and at its other end to the winding-shaft, spring-pressed pawls to engage the ratchet-wheels on the winding-shaft, a lever mounted at one of its ends on the operating-shaft near each of its ends, a bar pivotally and transversely secured on the other ends of said levers and adapted to engage the fabric, and spring-pressed pawls on the levers to engage 95 the ratchet-wheels on the operating-shaft, substantially as described.

6. In a bed-spring tightener, the combination with the tightener-frame, of a winding-shaft tapered from its middle to each of its 100 ends and an operating-shaft transversely journaled in parallelism on the frame near one of its ends, intermeshing gears and ratchet-wheels on one of the ends of said shafts, a web or fabric secured at one of its 105 ends to one end of said frame and at its other end to the winding-shaft, a spring-pressed pawl to engage the ratchet-wheel on the winding-shaft, a lever mounted at one of its ends on the operating-shaft and adapted to 110 engage with its other end the web or fabric, and a pawl on the lever to engage the ratchet-wheel on the operating-shaft, substantially as described.
